UNITED STATES PATENT OFFICE.

WILLIAM SCOTT, OF CENTRAL NYACK, NEW YORK.

NON-REFILLABLE BOTTLE.

1,069,482.

Specification of Letters Patent.

Patented Aug. 5, 1913.

Application filed August 8, 1912. Serial No. 713,981.

To all whom it may concern:

Be it known that I, WILLIAM SCOTT, a citizen of the United States, and resident of Central Nyack, in the county of Rockland and State of New York, have invented 5 certain new and useful Improvements in Non-Refillable Bottles, of which the following is a specification.

This invention relates to that class of 10 valves for bottles permitting the outflow of fluid therefrom, but preventing refilling thereof.

My improvements in brief comprise an 15 obstruction member placed in a bottle neck, or within a sleeve therein, said obstruction member having fluid channels, but being incapable of penetration by a wire; together with a pair of hemi-spheres whose convex surfaces are in opposed relation, said hemi- 20 spheres being loosely retained between the obstruction member and a lower flange or seat. In the drawing accompanying this 25 application, Figure 1 is a vertical section of a bottle neck portion with my improved non-filling device fitted therein. Fig. 2 is 30 a view of the same as tilted for outpouring; Fig. 3 is a section on the line 3—3 of Fig. 1; Fig. 4 is a top plan view of the obstruction member, and Fig. 5 is a top plan view of the upper valve member.

In the figures I have shown a sleeve *a* as containing my improved valve mechanism, said sleeve being fitted within the neck *b* of a bottle. But, obviously, said sleeve 35 may be dispensed with, and the valve parts directly contained within the bottle neck.

Fitting within the upper portion of sleeve *a* is what I term an obstruction member, which is composed of the head portion *c*, 40 body portion *d* and foot portion *e*, the portions *c* and *d* having an annular, separating groove *f* and the portions *d* and *e* having an annular, separating groove *g*.

The head portion *c* has an annular flange 45 *h* by which the obstruction member rests upon the upper edge of sleeve *a*. The head portion *c* is penetrated vertically by four, equidistant, radial holes *i*; the body portion *d* has four equidistant, radial, vertical slots 50 *j*, and the foot portion *e* has four equidistant, radial, vertical slots *k*. The holes *i* and slots *k* are in alinement, but are separated by solid parts of the body portion *d*, 55 because the slots *j* are in different vertical planes.

The purpose of the above noted arrange-

ment of holes and slots in the obstruction member is that a wire or the like, introduced through one of the holes *i* will not readily enter a slot *j*, but will be stopped by 60 a solid part of body portion *d*. If the wire with careful working should be caused to enter a slot *j*, then it would be positively checked against any further passage through the obstruction member by striking against 65 a solid part of foot portion *e*. Thus the obstruction member, while permitting fluid flow through its slots and holes, is impervious to the passage of an interfering wire or 70 the like. It therefore forms a valve protector, and is disposed in the bottle neck above the valve. The under surface of the foot portion *e* serves as an open valve seat, when the bottle is tipped to pour out the 75 fluid, and said under surface has the crossed grooves *l*, merging into the slots *k*, to facilitate the flow.

The valve comprises two hemi-spherical bodies, *m* and *n*, the body *m*, when the bottle is upright, lying with its plane surface 80 on seat *o* in sleeve *a*, or in the bottle neck; and the body *n* lying with its convex surface upon the convex surface of said body *m*. The body *n* has a central orifice *p*, whose circular edge at the convex side of 85 body *n* allows said body to seat centrally upon the convex surface of body *m*. Said body *n* also has peripheral slots *q* which merge into transverse slots *r* on the plane surface of body *n*, and allow the passage of 90 fluid from the bottle when the latter is tilted. The space between seat *o* and the under surface of foot portion *e* of the obstruction device is sufficient to allow movement of the hemi-spherical bodies *m* and *n* 95 in unseating the valve and permitting the passage of fluid when the bottle is tilted in pouring out the contents, but said space is insufficient to permit said bodies *m* and *n* to change from their relative operative positions. 100

In practice, a bottle equipped with my improved valve and obstruction device, cannot be refilled, for if the neck be filled with fluid, above the valve, and the bottle be 105 shaken, the valve will not allow the entry of the fluid within the bottle. Also by reason of the obstruction device it is not possible with wires to tamper with the valve. On the other hand, when tipping the bottle 110 to pour out the contents, the valve opens and permits free passage of the fluid.

I claim:—

A bottle having an annular shoulder in its neck, a valve-seat engaging said shoulder and having an opening, an obstruction device formed with staggered openings arranged above the valve-seat, a plurality of non-buoyant hemispherical valve members arranged between the valve-seat and obstruction device, one of said members being

5 solid and the other formed with an opening, said valve members having their rounded surfaces in contact at all times, with the flat side of the solid member normally form-

10

ing a valve for the opening in the valve-seat and the flat surface of the other member coöperating with the obstruction member in the pouring operation, the last-mentioned member serving to limit the opening movement of the solid member.

Signed at West Nyack, in the county of Rockland and State of New York, this 25th

day of May, A. D. 1912.

WILLIAM SCOTT.
